UNITED STATES PATENT OFFICE.

MAXWELL LUSTIG, OF BROOKLYN, NEW YORK, ASSIGNOR TO PETER BECKER, OF NEW YORK, N. Y.

TOY AIRSHIP.

1,288,946.

Specification of Letters Patent. Patented Dec. 24, 1918.

Application filed May 25, 1918. Serial No. 236,546.

To all whom it may concern:

Be it known that I, MAXWELL LUSTIG, a citizen of the United States, and a resident of the city of New York, borough of Brooklyn, in the county of Kings and State of New York, have invented a new and Improved Toy Airship, of which the following is a full, clear, and exact description.

This invention relates to toys and has to 10 deal more particularly with toys of the aerial type in the form of a flying machine of the lighter than air character.

The invention has for its general objects to provide a simple, novel and fascinating 15 toy which embodies a gas-inflated body for rendering the toy floatative and which has light flexible wings which assume different positions under the action of the air currents, and at one end of the body is a propeller 20 which rotates as the wind strikes it, so that the toy in action closely resembles a flying machine, to the great amusement and fascination of children.

A more specific object of the invention is 25 the provision of a novel wing construction, in combination with an air-inflated body, whereby the toy can be easily and cheaply constructed.

With such and other objects in view, the 30 invention comprises various novel features of construction and arrangement of parts which will be set forth with particularity in the following description and claims appended hereto.

35 In the accompanying drawing, which illustrates one embodiment of the invention and wherein similar characters of reference indicate corresponding parts in all the views,

Figure 1 is a perspective view of the toy; 40 Fig. 2 is a side view with the gas bag or body partly broken away; and

Fig. 3 is a sectional view on the line 3—3, Fig. 1.

Referring to the drawing, A designates 45 the body of the flying machine, which is made of toy balloon rubber or equivalent material and is adapted to be inflated with a gas lighter than air, the mouth of the balloon being provided with a cork or other 50 stopper 1. In this stopper is placed a pin 2 which forms a pivot for the imitation propeller B which is made from a piece of paper or other light material.

Attached to the top of the body A are

oppositely extending wings C which are 55 preferably formed of very light paper 3 pasted to the top of the body A, the front and rear edges of the wings being reinforced by flexible members 4 which are attached in any suitable manner, as, for instance, by 60 turning back the edges of the paper and glueing them around said members. Normally the wings are more or less in a common plane, but when the toy is in action the wind will cause the wings to incline upwardly in opposite directions from the body 65 to give a more or less realistic appearance of a flying craft.

A string D may be employed for holding the toy captive, such string having branches 70 5 and 6 at its upper ends for tying to the opposite ends of the body A.

The toy can be used in place of a kite and will float in such a manner as to simulate a flying machine with the propeller rotating, 75 or the toy can float freely in the air, and while the breezes carry it along the propeller will rotate and the wings assume an upwardly inclined position.

From the foregoing description taken in 80 connection with the accompanying drawing, the advantages of the construction and method of operation will be readily understood by those skilled in the art to which the invention appertains, and while I have described the principle of operation, together with the article which I now consider to be 85 the best embodiment thereof, I desire to have it understood that the article shown is merely illustrative and that such changes may be 90 made when desired as fall within the scope of the appended claims.

Having thus described my invention, I 95 claim as new and desire to secure by Letters Patent:

1. A toy comprising an inflated body, a strip of material attached at its medial portion to the top of the body, and stiffening elements fastened to the front and rear edges of the strip, whereby resilient wings are 100 formed, the connections between the wings and said body being flexible, whereby the wings are normally substantially in a common plane and adapted to swing upwardly and in an inclined position under the action 105 of the wind.

2. A toy comprising an inflated bag, a stopper closing the mouth thereof, a pin in

the stopper, a propeller on the pin, and wings attached to the body and extending from opposite sides thereof.

3. A toy comprising an inflated bag, a stopper closing the mouth thereof, a pin in the stopper, a propeller on the pin, wings attached to the body and extending from opposite sides thereof, and a holding string

fastened to the front and rear ends of the body.

4. A toy comprising an inflated body, a holding string attached to the ends thereof, a propeller on one end of the body, and wings extending from opposite sides of the body.

MAXWELL LUSTIG.
